FIREARM ACCESSORY

Frederick William Poate, Shanghai, China, assignor to Luther Samuel Moore, Newtonville, Mass.

Application July 11, 1934, Serial No 734,595

4 Claims. (Cl. 42—1)

This invention relates to firearm accessories and particularly to a novel type of mount adapted to be secured to the barrel of a firearm and, when in use, to be pressed against a supporting surface disposed in a plane substantially normal to the direction of fire, whereby to absorb both the upward and rearward components of the shock of recoil.

It has been common heretofore to steady the barrel of a firearm during fire either by the use of tripods, carriages or other suitable sturdy supports constructed for heavy ordnance or, in lighter firearms, by the simple expedient of resting the barrel on any convenient support. So far as I am aware, however, there has not been available heretofore a steadyng and shock absorbing device which is practical for use with lighter firearms such as revolvers, automatic rifles and the like, and which not only does not add materially to the weight of the firearm, but which also is so adapted for co-operation with any convenient fixed support as to absorb both the rearward and upward components of the recoiling force.

25 It is my purpose to provide such a recoil absorbing device and I have found that if the firearm barrel be not only supported from beneath but also be secured in a direction longitudinal of the barrel, the recoil, both in its vertical and horizontal components, will be effectively absorbed. To that end it is the primary object of my invention to provide a device which is attachable preferably to the forward end of the firearm barrel and which is adapted to co-operate with a fixed support presenting supporting surfaces in planes both normal and parallel to the direction of fire, whereby effectively to support the barrel and to secure it against longitudinal movement.

40 I have found further that if the longitudinal securing be effected by drawing the barrel in a direction opposite to the direction of fire, or toward the rear of the firearm, and bracing it in that direction against a vertical support, the combined rearward and upward components of the recoil will act to jam the gun barrel still more firmly against the supporting surface which is normal to the axis of the barrel and thereby effectively absorb the recoil and prevent any material deflection of the barrel from its target. In this manner I obviate the necessity for re-aiming before each shot as has heretofore been necessitated by the deflection of the barrel incident to the recoil and I thereby materially enhance the accuracy of fire particularly in repeating fire-

arms in which the discharges are in rapid succession.

These and further objects and advantages of my invention will appear from a more detailed description thereof taken in connection with the accompanying drawing in which:—

Fig. 1 is an elevation view showing my device in use, secured to the barrel of a rifle;

Fig. 2 is an enlarged vertical sectional view on the line 2—2 of Fig. 1;

Fig. 3 is a vertical sectional view on the line 3—3 of Fig. 2; and

Fig. 4 is a perspective view of the elements of my novel mount shown in position to be assembled.

As indicated in the drawing and particularly Fig. 4, my device comprises a pair of similarly shaped clamping members indicated generally at 1 and 2, each of which members is provided with a semi-cylindrical bore 3 which, when the parts are assembled, will conform generally to the external cylindrical curvature of the barrel of the firearm to which it is to be attached. The separable clamp members 1 and 2 are preferably shaped substantially as indicated and they support, preferably integrally therewith, the shock absorbing portions 7 and 8, each of which is also provided with a semi-cylindrical bore 5 which extends through the face 6 of each member but terminates short of the opposite face of the member in a wall 10 preferably integral with the member and closing that end of the bore. The radius of curvature of the semi-cylindrical bores 5 is preferably in substantially the proportion indicated and when the separable members 1 and 2 are assembled as indicated in Fig. 2, the combined, juxtaposed recesses 5 form a cylindrical chamber to receive and secure a plug 11 which is preferably composed of resilient material having a high coefficient of friction as, for example, rubber. Screws 12 cooperate with the aligned screw threaded orifices 13 to secure the sections of the clamp and shock-absorbing members together in an obvious manner.

In use the screws 12 are loosened or removed as required and the clamp members are positioned on the forward end of the barrel 20 of the firearm, as indicated in Fig. 1, and with the wall portions 10 of the shock absorbing members 7 and 8 facing forwardly. The resilient plug 11 is inserted in the lower, juxtaposed recesses 5 from the rear, with the end 21 of the plug abutting the now combined end walls 10 of the recesses, and in this manner a substantial portion 22 of the plug will protrude outwardly beyond the faces 6 of the

members 7 and 8 to present a buffer surface which is substantially normal to the direction of fire, or may be so inclined that lower edge of buffer is the first to engage the front surface of 5 support.

When it is desired to fire the gun the barrel is rested on any convenient support 30 which preferably presents a supporting surface 31 lying in a substantially horizontal plane and a second 10 supporting surface 32 in front of the support 30 and in a plane substantially normal to the direction of fire. The firearm is then drawn rearwardly until the surface 22 of the resilient plug 11 abuts the surface 32 and the firearm is 15 continually pressed in this manner against the support 30 during fire.

It will be apparent that the rearward component of the recoil will be effectively absorbed by the support 30 and resilient cushion 22 which 20 thereby act to cushion the shoulder of the firer against impact. It will also be noted that the rearward horizontal component of the recoil will act to increase the pressure between the support 30 and the frictional buffer surface 22 at the instant when the barrel tends to turn upwardly with the result that any material upward deflection is effectively restrained. The firearm does not therefore require re-aiming before the next 25 shot is fired and repeating firearms can be discharged in rapid succession without the inaccuracy which has heretofore resulted from upward kicks of the barrel at each shot.

The preferred embodiment of my invention herein described is subject to variation within 30 the spirit of my invention which is to be limited only as indicated in the appended claims.

I claim:

1. As a firearm accessory, a device for absorbing the shock of recoil comprising attaching 35 means adapted to be secured to the firearm barrel and a resilient medium projecting from said attaching means, said attaching means being recessed to receive and grip said resilient medium

to present a buffer surface adapted to abut the forward surface of a support positioned to the rear of said attaching means.

2. As a firearm accessory, a device for absorbing the shock of recoil comprising separable 5 clamp means bored internally to conform to the external curvature of the firearm barrel and adapted to be secured to said barrel, said clamp means having a portion projecting therefrom, and shock absorbing means extending from said portion rearwardly with respect to the muzzle of the gun, to abut the forward surface of a support positioned to the rear of said projecting portion, said projecting portion including a cupped recess and said shock absorbing means comprising 10 a resilient medium received in said recess.

3. As a firearm accessory, a device for absorbing the shock of recoil comprising attaching 15 means adapted to be secured to the firearm barrel and a resilient medium projecting from said attaching means, said attaching means being recessed to receive and grip said resilient medium 20 which projects therefrom and presents a buffer surface, in a plane substantially normal to the line of fire and rearwardly with respect to the muzzle of the gun, to abut the forward surface of a support positioned to the rear of said attaching means and thereby translate the shock of recoil of the firearm to said forward surface 25 of the support.

4. A firearm accessory for absorbing the shock of recoil comprising attaching means adapted to be secured to the firearm barrel and shock absorbing means projecting from said attaching means and presenting a buffer surface adapted to abut a supporting surface substantially normal to the line of fire, said buffer surface being 30 presented rearwardly with respect to the muzzle of the gun and being so inclined from a plane normal to the line of fire that the lower edge 40 of the buffer surface is the first portion of said buffer surface to engage the supporting surface.

FREDERICK WILLIAM POATE.
